UNITED STATES PATENT OFFICE.

HENRY L. KINTER, OF CURRAN, ILLINOIS.

PENHOLDER.

No. 845,178.

Specification of Letters Patent.

Patented Feb. 26, 1907.

Application filed August 26, 1905. Serial No. 275,810.

To all whom it may concern:

Be it known that I, HENRY L. KINTER, a citizen of the United States, residing at Curran, in the county of Sangamon, State of Illinois, have invented certain new and useful improvements in Penholders; and I do hereby declare the following to be a full, clear, and exact description of the invention, such as will enable others skilled in the art to which it appertains to make and use the same.

This invention relates to penholders, and it has for its object to provide a structure that may be manufactured at a minimum cost, that will comprise but few parts, and which while holding a pen securely in place may be easily manipulated to release the pen when desired.

In the drawings forming a portion of this specification, and in which like numerals of reference indicate similar parts in the several views, Figure 1 is a longitudinal sectional view through a penholder embodying the present invention. Fig. 2 is a detail view of the pen-clamping spring.

Referring now to the drawings, there is shown a penholder comprising a handle 5, having a reduced end portion 6, upon which is fitted a sleeve 7 similar to the pen-receiving sleeve of the usual holder with the exception that through the upper wall there is formed an opening 8.

The pen-point 9 is held against the upper portion of the inner face of the sleeve 7 by means of a spring-plate 10 of U shape, one arm of which is shorter than the other and is riveted or otherwise secured against the bot-

tom of the inner face of the sleeve. The upper longer arm of the spring-plate is the clamping-arm, and struck up from this upper arm directly adjacent to the vise portion 11 of the plate is a finger 12, that extends upwardly through the opening 8 and is bent over, as shown at 13, exteriorly of the sleeve. When the button 13 is pressed toward the sleeve 7, the clamping-arm of the spring-plate is forced away from the upper portion of the sleeve and releases the pen-point 9.

What is claimed is—

A penholder comprising a pen-receiving sleeve provided with an opening in its wall, a resilient pen-clamping strip arranged within the sleeve, said strip being of the same width throughout and having one of its ends bent downwardly and beneath its body portion and secured to the sleeve at a point opposite the opening therein, the said strip having its body portion bearing against the side of the sleeve in which the opening is formed and being adapted to clamp a pen therebetween and the said side of the sleeve, and a finger formed upon the strip by stamping up a portion of the strip rearwardly of the opening in the sleeve so that the said portion extends through the opening and bending the upper end of the said portion in a forward direction to form a head, substantially as described.

In testimony whereof I affix my signature in presence of two witnesses.

HENRY L. KINTER.
